APPARATUS FOR PROTECTING OIL DISTRIBUTION MEANS AT HARBORS

Walter W. Macfarren, Los Angeles, Calif.

Application March 25, 1938, Serial No. 198,093

9 Claims. (Cl. 137—78)

My invention relates to a means for protecting harbors and cities from the destructive effects of "wild" or free oil, escaping from pipe lines, due to accidental or man made leakage, or the convulsions of nature.

The invention is generally applicable to any harbor, city, or vicinity where the area is congested with surface or underground pipe lines carrying large quantities of oil.

At any harbor where large quantities of oil are transferred to ships, more or less dangerous conditions exist, since the oil is usually stored above ground, and the ground is always above the water level. Thus if pipe lines are ruptured, the oil runs downhill and spreads over the water, and may reach all the docks and ships in the harbor, if a sufficient amount of oil runs free.

Broadly stated, the objects of the present invention are:

- 20 1. To limit the amount of oil which may escape from a ruptured pipe line.
2. To render the operation of the apparatus automatically effective upon the occurrence of an earthquake of even minor intensity, which may be the precursor of greater shocks.
3. To provide manual controls for operating the apparatus from a central control station.
4. And to provide the detailed structures for operating them, now to be described.

30 In the appended drawings:

Fig. 1 is a diagram showing a plan of a harbor.

Fig. 2 is a diagram of a control station.

Fig. 3 is an elevation of storage tanks and pipes.

Fig. 4 is an elevation of automatic pipe line valves.

Fig. 5 is a plan of group controls for the same.

40 Fig. 6 is a vertical section of an air valve.

Fig. 1 shows diagrammatically, a man made harbor, in which the shore line is shown at 50, a breakwater or sea wall at 51, and a second sea wall at 52. It is assumed that there are a pair of opposite hills, 53 and 54, and between these hills there is built an embankment 55, which may have a width of from one hundred to several hundred feet, and which may be covered with streets and buildings. If the hills 53 and 54 do not exist, the embankment 55 may extend to the shore line at points outside the sea walls 51 and 52, as indicated at 49.

Railroad tracks 56 may enter the harbor area through a gate 57 and a similar gate 58, may be provided for very heavy vehicular traffic.

Ordinary traffic may be carried over the embankment 55.

All the land surrounding the harbor falls naturally to the water's edge, and at the north side, a natural slough 59, or drainage channel, 5 may be assumed to enter the harbor. The embankment 55 may be carried over this, and a water gate 60 may be provided as shown, to allow the discharge of flood waters.

Extending up the slough 59 to the north, 10 there are presumed to be a number of large tank farms, or groups of oil storage tanks 61—67, and other similar tanks may be located in nearby territory, as shown at 68—70.

Within the embankment 55 there are presumed to be other oil storage tanks of large capacity, as shown at 71—75. All of these latter tanks may be close to the water, and some of them may be on docks, for transfer of oil to ships. Pipe lines of large size are indicated at 20 76—80, for connecting the near and distant tanks.

There may be from 50 to 100 of these connecting pipe lines, and it is assumed that the whole water front is surrounded by factories, stores, 25 dwellings, and the various units which comprise a city. This built up area may extend back for several miles from the water front, and the connecting pipe lines 76—80 may pass through it, 30 and underground.

In Fig. 1, two artificial islands 81 and 82, are shown, which are provided with piers or docks 83, and slips 84. An opening 85 is provided in the breakwater 51, which leads into the outer 35 harbor 86, from the sea. Ships at anchor are indicated at 87 and 88, and a main channel is shown at 89. The layout shown in Fig. 1 provides three main protected basins A, B, and C, and a smaller basin D, for fishing boats or 40 yachts. These conditions are similar to those obtaining at Los Angeles Harbor, except that the embankment 55 does not now exist.

With the above assumed conditions, there are three main possible elements contributing to a 45 major catastrophe by fire. One is the possibility of a stream of oil flowing down the slough 59 to the water front, from ruptured oil tanks outside of the embankment 55, and flooding the harbor waters with floating oil.

A second is the damage to the surrounding portions of the city outside of the embankment, from ruptured tanks or pipe lines, and a third is the danger from oil spreading over the water surfaces of the main channel 89, and the basins 55

A, B, C, and D, from a rupture of some of the close-in oil tanks 71—75.

The purpose of the embankment 55 is obviously to shut off any flow of oil from points outside of it, toward the harbor waters. It has been previously pointed out, that most or all, of the oil storage tanks are provided with a surrounding wall to keep the oil from spreading if the tank is ruptured. It has also been stated that such walls may be easily breached by sabotage, and they might also be overthrown by an earthquake.

While the embankment 55 is also a dam or dike, it is of large size, and preferably an earthen fill, and may be made of such width that many bombs might fail to breach it and sabotage could be made very difficult. Even an earthquake of major proportions would not necessarily prevent its retention of wild oil.

To prevent the outflow of oil into the city streets and sewers, upon the rupture of one or more pipe lines, I provide automatic valves on such lines, which may be manually controlled, either singly or in groups, or which may be automatically closed by the first effects of an earthquake.

In order to synchronize these various controls, I provide one or more central control stations, preferably two such stations, as indicated at 90 and 95.

These stations are shown as located on the hills 53 and 54, at opposite sides of the harbor, but this location is a matter depending on many circumstances, and as shown is merely illustrative.

It is assumed that one or more operators would be in attendance at each station 90 and 95, day and night. In order to control the various oil valves from such central control stations, the control medium must have the characteristic of certain and reliable operation, when many of its operated parts are put out of commission by an earthquake. In other words, normal conditions are maintained when the control connections between the control stations and the operating apparatus are in good order, and automatic operation of the valves is effected when the controlling medium is disconnected from the control stations, either purposely or by accident. Successful automatic operation depends in part upon the failure of some of the controlling connections, as will appear later.

To achieve such results I employ compressed air, or other elastic gas, as a controlling medium. This air is under static pressure in tanks and pipes, and may be so held at low cost (for leakage only), until definite action is demanded, at which time it may act promptly and reliably.

It may be noted in passing that electric current is not suitable for such controls, for if desired emergency action depends on the supply of current, such supply might easily be cut off by an earthquake, or by sabotage, and if the desired emergency actions are effected by gravity, springs, or other ready forces, a continuous current supply would be necessary to prevent such forces from acting until desired, which would be a constant expense for current, and the devices would be subject to undesired application upon a failure of current supply. On the other hand, a tight air pipe line filled with air under pressure, is subject to practically no operating expense.

In Figs. 2, 3, 4, 5 and 6, I have illustrated protective means for the various pipe lines 76—80

leading from any of the tank farms 61—70 to the close-in storage tanks 71—75. In Fig. 3, the outer storage tanks 61—70 may be assumed to be located on higher ground than the close-in storage tanks 71—75, and both sets of tanks are 5 above the harbor water level 111.

If any of the outer tanks 61—70 are ruptured, the embankment 55 will stop the flow of oil toward the harbor, but if only one of the pipe lines 76—80 is ruptured, the oil contained in the pipe, 10 and some of the oil in the tank will flow into the city streets and sewers, between the place of rupture and the embankment 55, or between the place of rupture and the harbor water edge, if the rupture occurs within the embankment. 15

It is to be remembered that some of the pipe lines 76—80 may be several miles long, and some of them may pass for a mile or more under busy city streets. Therefore it is a matter of prime importance to minimize the amount of oil which 20 might escape from a ruptured pipe line, and more important still to minimize the escape of oil when many of these pipe lines are ruptured at the same time, as by an earthquake.

To achieve such results, I propose to subdivide 25 each of the oil carrying pipe lines 76—80 into sections of a length determined by the size and capacity of the line, whether it carries crude oil or gasoline, the slope or fall of the line from the storage tanks 61—70, the character of the buildings or of the stored materials on the surface above the line, the funds available for protective purposes, and other considerations. 30

To do this I supply spaced automatic valve apparatus, which may be designated as a whole 35 by numeral 112. Referring to Fig. 4, this apparatus may consist of a gate valve 23, or other suitable type of valve, on one of the oil pipe lines 76—80, arranged to be opened or closed by a double acting air cylinder 22, having a piston 30. 40 For each valve 23 to be operated, there is a small tank 20, which is kept supplied with compressed air at say 100 pounds pressure, through a small pipe 27 leading to one of the control stations 90 or 95. 45

The air may pass from the pipe 27 to the tank 20 through a bent tube 24, of brittle material, such as thin cast iron, or glass, the latter being preferred, and which an earth tremor may easily 50 break. Between the tube 24 and the tank 20, there is a check valve 25, to prevent escape of air from the tank 20.

A special four way valve 28, to be described in detail later, is set between the tank 20 and the cylinder 22, and air is supplied to the valve 28 by a pipe 33, from the tank 20. A second pipe 26 supplies air to the valve 28, from a point in the line 27, beyond the breaker section 24. 55

When the line 27 is under full normal pressure, the tank 20 is also under normal pressure, and the air from pipe 26 sets the valve 28, so that air flows through pipe 21 to the front end of the cylinder 22, and operates the piston 30 to open the main gate valve 23. If however, the pressure in the line 27 is purposely released by the operator in a control station 90 or 95, or if the breaker section 24 breaks, or if any other section of the line 27, between the tank 20 and the control station fails, then the valve 28 is so actuated by this release of pressure in the pipe 26, that the pressure of the stored air in the tank 20, is released from pipe 21, and applied to pipe 29, thus pushing the piston 30 to the left, and closing the main gate valve 23, to shut off the flow of oil in one 70 75

of the main oil lines 76—80, or any similar pipe line to which the valve 23 may be applied.

The speed of action of the piston 30 may be controlled or modified by one or more small oil cushioning cylinders 34, of well known types, connected to the piston rod 32 by a rocker arm 35, or other suitable means. The operation of the main gate valve 23 may be tested manually by a 3-way valve 31, in the pipe 26.

10 It will be noted that this is emergency apparatus, and it must operate with certainty and promptness. When the breaker section 24 is ruptured by an earthquake, the action is immediate, since the required motive force is stored in the 15 tank 20, ready for instant action.

If however, the control is exercised from the control station 90 or 95, and this is a mile or more distant, some few seconds may elapse before the reduction of pressure in line 27 is sufficient 20 to change the setting of the valve 28, to actuate the piston 30 to close the main valve 23.

The air lines 27 may be small, since there is ample time available to recharge the tank 20. These lines may be laid in ditches, carried over 25 houses, strung on telephone poles, or laid in sewers, or even in the inside of the oil carrying pipe lines.

They may be easily diverted, detoured, or concealed to render sabotage difficult, or impossible. 30 While the apparatus just described has for its prime purpose the prevention of loss of oil from pipes, to avoid the fire hazard due to wild oil, and is not primarily for the purpose of conserving the oil itself, yet by preventing free escape, 35 it also saves the oil.

Fig. 6 shows one suitable form of the valve 28, in vertical section. This comprises a hollow casting having two aligned cylindrical bores 36 and 37, in which may be mounted a plunger 38, having 40 a collar 39, and a spring packing ring 41, the bores 36 and 37, being respectively provided with cylinder heads 42 and 43.

A coiled spring 44 may be placed between the head 42, and the end of the plunger 38, of sufficient strength to move the plunger and the connected "D" valve 40, when there is no air pressure supplied to the bore 37 from the air line 26. The valve 40 operates on a flat valve seat 45, having 45 an exhaust port 46, and two cylinder ports 47 and 48.

The pipe 33 supplies pressure to the inside of the valve 28, and the port 48 supplies pressure to the pipe 21, to open the main gate valve 23, when pressure exists in the pipe 26. When there is no 50 pressure in the pipe 26, the spring 44 moves the plunger 38, and the connected valve 40 to the right, which exhausts the air from the pipe 21, through the port 46, and permits air to flow from pipe 33 and port 47, to pipe 29, and to the right 55 end of cylinder 22, thus closing the main gate valve 23, and shutting off the flow in one of the oil lines 76—80.

Instead of having the breaker member 24 located as shown on the pipe 27, it may form a 60 part of the pipe 26, as indicated in dotted lines in Fig. 4. It is also to be noted that such breaker sections may be located at other points along the line 27, between the tank 20 and one of the control stations 90 or 95, so that more certain operation 65 might be had in case of a minor earthquake, or a local explosion.

Fig. 5 is a diagram showing a possible arrangement of several sets of automatic valve apparatus 70 112, to control several pipe lines 76—79, in parallel relation such as might occur in a city

street. If such lines are not conveniently parallel as shown, they could be re-located at this point.

The several sets of apparatus 112 may be set 5 in a concrete vault 113 under the street, which may be reached by stairs 114, from a small house 115, on adjoining property. An air line or group control pipe 117 may be led from one of the control stations 90, or 95, to the house 115, or to a store or other occupied building 10 nearby. From the pipe 117, branch pipes 27 may lead to each tank 20, and each pipe 27 may have a 15 3-way control valve 116, which may be operated independently to exhaust the contained air from one of the pipes 27, thus allowing the associated main gate valve 23 to shut off one of the main oil pipe lines 76—79.

If a telephone message is received at one of the control stations to shut off line 76 at the 20 point shown in Fig. 5, this message may be relayed to the store operator, who may open the appropriate valve 116, and report back to the control station. If such report is not promptly forthcoming, the operator at the control station 25 may exhaust the air from the group control line 117, and thus close all the main gate valves 23 at this point, or in his judgment, he may close them all at first, without calling the store operator.

The air pipes connecting any of the apparatus 30 herein described may be of ordinary steel pipe, drawn steel tubing, or copper tubing, which latter is proof against rust, but more expensive.

The use of a non-oxidizing gas such as 35 carbon dioxide would be conducive to protecting the interior of steel pipes against rust caused by the water vapor in compressed air, and such gas may be easily generated, and might be used in any of the piping herein described as a working fluid, instead of compressed air.

The diagram Fig. 2 illustrates the relation of 40 the control station 90 and 95 to the various pieces of apparatus previously described. Each control station is provided with an independent air compressing plant comprising one or more compressors, each preferably provided with two independent sources of motive power, such as 45 electric and gasoline motors.

In addition, each station may be provided with 50 one or more air storage tanks, and a fuel oil or gasoline tank, all of these being preferably under ground.

The prime purpose of having more than one 55 control station is that if one is put out of commission the other may still function, although other advantages also accrue, such as giving better visibility over a wide area such as a modern harbor, and the provision of duplicate personnel at each station, for emergencies.

If there are two stations as shown in Fig. 1, and one of them put wholly out of commission, from any cause, it will be useless, but minor accidents to machinery or piping may occur, in which case one station could assist the other.

To obtain the fullest possible co-operation between the stations, they should be connected by telephone, telegraph, and electric power lines, and also by fuel and air lines, so that fuel or air pressure lacking at one station could be supplied by the other. Such interconnecting service lines could be aerial, subsurface, or submarine lines, or of all three types.

With two stations located approximately as 75 shown in Fig. 1, it would probably be desired that

each station should control the apparatus located in approximately one half of the harbor area. This has been assumed in Fig. 2, and only one station 90 will be described. Various service lines are shown between the stations at 160. An air compressor and its driving means is indicated at 161, air storage tanks at 162, and a fuel storage tank at 163. A main air line 164 leads from the air tanks 162 to a header 165, preferably located in the control room.

From the header 165, branch lines 166 may lead to various groups of automatic valve apparatus 112, controlling oil pipe lines such as 76—80, or to a single important valve.

Each air line having a separate function may be provided with a 3-way valve 170, so that air pressure may either be maintained in, or exhausted from that line.

To sum up, the present invention provides protective devices for oil in pipe lines contiguous to a harbor, or city, and adapted to minimize the fire hazard, and to some extent the loss of the oil, as follows:

Protecting valve apparatus for oil pipe lines located under city streets, or leading toward a harbor, which will retain the major portion of the contained oil in the pipes, in case of rupture thereto, and which may either be closed by an operator in a distant control station, or which will shut off such oil flow automatically upon a distinct earthquake shock.

The value of the above described protective devices depends first, upon the fact that an earthquake may rupture many pipe lines containing oil, without destroying the port or the shipping therein; and second, that extensive, carefully planned, and skillfully executed acts of sabotage may produce practically the same effect. In either case, without some such protection, the entire port may be consumed by fire, including that portion of the shipping unable to get out to sea.

I claim as my invention all the patentable subject matter covered by the following claims.

1. Apparatus for controlling the flow of fluid through a pipe line, comprising a main stop valve in said line, a conduit which may contain an elastic gas under pressure, a pressure reservoir supplied by said conduit and adjacent to said main valve, means for preventing the escape of elastic gas from the reservoir through said conduit, means operated by pressure from said reservoir for opening and closing said valve, and means for controlling the application of said pressure in a manner to effect opening of said valve when pressure in said conduit is above a predetermined value, and in a manner to effect closing of said valve when the pressure in said conduit is below said value.

2. Apparatus for controlling the flow of fluid through a pipe line, comprising a main stop valve in said line, a conduit which may contain an elastic gas under pressure, a pressure reservoir supplied by said conduit, and adjacent to said main valve, means for preventing escape of pressure from said reservoir to said conduit, pressure operated means for opening and closing said valve, means for controlling the application of pressure in a manner to effect opening of said valve when the pressure in said conduit is above a predetermined value, and in a manner to effect closing of said valve when the pressure is below said value, the pressure for closing said valve being supplied from said storage reservoir.

3. Apparatus for controlling the flow of fluid

through a stationary pipe line, comprising a main stop valve in said line, a reservoir of compressed gas adjacent to said valve, a fluid pressure motor for opening and closing said main valve, means for supplying compressed gas from said reservoir to said motor including an automatic pressure operated valve for reversing said motor, means for keeping said automatic valve normally set to keep said main valve open, and for automatically reversing said automatic valve to close said main valve upon the occurrence of an earthquake, or similar shock to the apparatus.

4. Apparatus for controlling the flow of fluid through a pipe line, comprising a main stop valve in said line, a reservoir of compressed gas adjacent to said valve, a fluid pressure motor for opening and closing said main valve, means for supplying compressed gas from said reservoir to said motor including an automatic pressure operated valve for reversing said motor, a piston controlling the position of said automatic valve, a cylinder therefor, a threeway operating valve at a distant point, a conduit connecting said threeway valve and said cylinder, and a spring opposing said piston, whereby the pressure in the conduit effects the opening of said main valve, and release of said pressure operates to close said main valve.

5. Apparatus for controlling the flow of fluid through a stationary pipe line, comprising a main stop valve in said line, a reservoir of compressed gas adjacent to said valve, a fluid pressure motor for opening and closing said valve, a source of compressed gas at a distant point, a conduit leading from said point to said reservoir, means for preventing escape of gas from said reservoir into said conduit, means for supplying pressure from said reservoir to said motor to open said main valve when pressure above a predetermined value exists in said conduit, and to supply pressure from said reservoir to said motor to close said main valve upon a reduction of pressure below said predetermined value, and a breaking section in said conduit which may be broken by a minor earthquake to cause said main valve to close.

6. Apparatus for controlling the flow of fluid through a pipe line, comprising a main stop valve in said line, a fluid pressure motor for opening and closing said valve, a conduit which may contain an elastic gas under pressure, a pressure reservoir supplied by said conduit and adjacent to said main valve, means for preventing escape of gas from said reservoir to said conduit, means controlling the application of pressure from said reservoir to said motor in a manner to open the valve when the pressure in the conduit is above a predetermined value, and in a manner to close said valve when the pressure in the conduit is reduced below said predetermined value, a valve in said conduit for lowering said pressure located adjacent to said main stop valve, and a second similar pressure lowering valve located at a distant control point.

7. Apparatus for controlling the flow of fluid through adjacent pipe lines, comprising a main stop valve for each of said lines, the said valves being adjacent to each other, an air motor for opening and closing each of said valves, an individual air reservoir for each of said valves, individual conduits to supply each of said reservoirs with compressed air, means for preventing escape of air from said reservoirs to their respective conduits, means controlling the application of pressure from the several reservoirs to their re-

spective motors in a manner to open one of said main valves when the pressure in its respective conduit is above a predetermined value, and in a manner to close said valve when said pressure in said conduit is reduced below said predetermined value, separate means for lowering the pressure in each of said conduits located near each of said main valves, a single conduit connecting with all of the said individual conduits 10 and leading to a distant control point, and a valve in said single conduit for reducing pressure therein to obtain the simultaneous operation of all said main valves.

8. A system of protective controls for oil carrying pipe lines, comprising one or more main stop valves in said line or lines, a central control station having a source of compressed air and a main air reservoir, a fluid pressure motor at each of said main stop valves arranged to open 15 and close said valve, an auxiliary reservoir nearby each of said main valves, an air pipe connecting said main reservoir with each of said auxiliary

reservoirs, means for preventing escape of air from said auxiliary reservoirs to said air supply pipes, means at the control station for admitting compressed air to each of said air pipes to charge said auxiliary reservoir connected thereto, or for 5 exhausting air from said air pipe to lower the pressure therein, and an automatic control valve located between each auxiliary reservoir and its connected fluid pressure motor, said valve being responsive to full air pressure in said air pipe 10 so as to operate said motor to open said main valve, and also responsive to a decrease in pressure so as to operate said motor to close said main valve.

9. The elements of claim 8, in combination with 15 a breakable air container connected to each of said air pipes, which may be broken by a minor earthquake to automatically release air pressure from said pipe to cause the air motor controlled thereby to close its connected main valve. 20

WALTER W. MACFARREN.
